INDUSTRIAL FURNACE

Kenneth W. Stookey, Cleveland, Ohio, assignor to
 The Gas Machinery Company, Cleveland, Ohio,
 a corporation of Ohio

Application February 10, 1943, Serial No. 475,365

6 Claims. (Cl. 263—7)

The invention particularly relates to improvements in industrial furnaces of various types, and is concerned primarily with improved vapor-removing mechanism that is incorporated with the furnace structure to prevent vapors from a liquid sealing medium coming into contact with the furnace charge. The invention is illustrated herein by a showing and description of a rotary forging furnace with which the improvements are incorporated.

Several advantages attach to the invention:

It can be installed on any liquid sealed portion of a furnace to remove vapors from the sealing medium.

It obviates glaring weaknesses in the furnace wall induced by certain other structures provided for vapor-removing purposes.

It enables certain operating economies to be effected.

It provides a constant result which can easily and definitely be varied to suit varying conditions.

Other and related advantages due to the instant improvements in industrial furnaces will be hereinafter mentioned by reference to the following description and the accompanying drawing.

The annexed drawing and the following description set forth in detail certain means illustrating the improved industrial furnace, such means constituting, however, only one of the various forms in which the principle of the invention may be embodied.

In said annexed drawing:

Figure 1 is a vertical axial section of a rotary forging furnace with which the invention is incorporated;

Figure 2 is a plan section, taken in part from the planes indicated by the line 2A—2A, Figure 1; in part from the plane indicated by the line 2B—2B; and in part from the plane indicated by the line 2C—2C;

Figure 3 is a view on an enlarged scale of one of the suction nozzles shown in Figure 1; and

Figure 4 is a plan view of the suction nozzle shown in Figure 3.

Referring to the annexed drawing in which the same parts are indicated by the same respective numbers in the several views, an oil or gas-fired rotary forging furnace 1 has a wall and dome structure surrounding a hearth and comprising an exterior side wall 2 combined with a dome 3, the hearth being shown herein as a rotating table 4, the assembly providing a combustion chamber 5 between the dome 3 and table 4, all as it well

understood by those versed in the art. The table 4 has clearance from the side wall 2 as indicated by the space 6. Waste gas flues 7 are formed in the side wall 2 and communicate with the combustion chamber 5 through ports 8 whereby the waste products in the combustion chamber 5 are withdrawn therefrom. A water seal casing 13, in the form of an annular trough, for a water-seal 12, surrounds and is secured to the rotatable table 4, preferably being built integrally with the table casing. The clearance area 6 opens at its bottom into the space above the water seal 12. Since the seal trough 13 is supported by the rotatable table 4, it can be and is extended outwardly of the furnace wall 2 and thus permits easy cleaning of the water trough 13 since its outer part is easily reached.

The main support for the side wall and dome structure and the rotatable table 4 is a sub-base 14 formed of I-beams and mounted upon these beams, in a manner not shown, are vertical I-beams 18 which form bases for jack screws 15 mounted thereon and cooperating with nuts 16² welded to horizontal plate portions 16¹ of housings 16 which enclose the upper ends of the I-beams 18 and upon the side surfaces of which they are slidable. The housings 16 are welded to the steel casing of the furnace wall 22. Thus, the furnace side wall and dome structure can be vertically adjusted, relatively to the rotating table 4, and the table clearance space 6 varied in cross-sectional area, since the spaced opposed surfaces of the furnace wall 2 and the hearth 4 defining the clearance area 6 are sloped and are also substantially parallel, as shown and described in the patent on Industrial furnaces, of Lazenby C. Hamlink, No. 2,316,580.

Other features of the furnace with which the invention is incorporated and shown in the accompanying drawing, to which reference will be here briefly made, and which are more or less standard, include burners 22 for firing the furnace, a charge and discharge opening 23, an air curtain 24, a water-cooled shield 25, a seal overflow pipe 26, a lifting lug 27 for manipulating the wall and dome structure, a lifting lug 28 for manipulating the sub-base and the unitary table and seal structure, table-supporting beams 29, spaced turntable rollers 30 rotatably mounted on the sub-base 14, an annular track 31 depending from the beams 29 and engaging the rollers 30, a worm and gear drive 32, and a centering pin structure 33.

It is highly important that in the operation of furnaces of the character herein under consid-

eration the vapors from the liquid seal, which kind of seal is most satisfactory for certain types of furnaces, for instance rotary and car-type furnaces, be prevented from entering the combustion chamber 5. In many types of furnaces including the types just specifically mentioned, it is also highly important that the entrance of infiltrated atmospheric air to the combustion or heating chambers be prevented. If the entrance of liquid vapors and atmospheric air can be prevented, the maintenance of a constant furnace atmosphere is thereby better insured, with the production of quality products and without the use of an excessive amount of fuel. Particularly, the scaling of the stock and surface decarburization thereof are prevented. In the form of furnace shown in the accompanying drawing, the slugs or stock are carried by the rotating hearth 4 from a charging opening to a discharge opening during the heating operation, as is well known to those skilled in the art, the charging and discharging of the stock oftentimes being effected through the same opening, as is true of the opening 23 shown for purposes of illustration in the accompanying drawing.

Various expedients have been devised for preventing entrance to the combustion chamber of seal vapors and atmospheric air, amongst which have been the provision of a wall duct adjacent the bottom of the table clearance area and communicating with the waste product vents, and also the provision of somewhat deeper waste product vents which communicate through ports in the side wall with the clearance area substantially below the upper level of the hearth. These expedients have not provided a constant draw of the vapors and air, nor one which could be easily and definitely controlled. Furthermore, the provision of an extra and lower vapor and air withdrawing duct adds a glaring weakness to the wall section or tile cored therefor.

The improvements which are presented in the instant application obviate the disadvantages just mentioned and, furthermore, produce operating economies which will be hereinafter fully described.

For withdrawing the seal vapors according to the instant invention, a plurality of nozzles 17, preferably of the shallow and wide-mouthed formation shown in Figures 3 and 4, are provided, of sufficient size and in whatever spacing are found suitable and necessary, which nozzles 17 intersect the dip plate 11 depending from the furnace side wall 2 into the seal 12 and tap the area adjacently above the seal 12. Pipes 19 leading to these nozzles 17 communicate with a header pipe 20 which surrounds the furnace 1 adjacently exteriorly of the side wall 2, and which in turn communicates through a pipe 21 with a Venturi section 10¹ in a pipe 10 leading from the motor-operated blower 9. A valve 10² in the pipe 10 serves to control the intensity of the suction and a valve 21¹ in the pipe 21 serves to throttle the suction. If suitable pressure burners are used for heating the furnace, the power for aspirating by the nozzles 17 can be obtained by using low pressure air from the blower furnishing combustion air; for instance, from the combustion-air-furnishing pipe 34. Otherwise, low pressure air for aspirating can be obtained from any other suitable device or source, or compressed air or steam can be used. In the event that a deoxidizing or carburizing controlled atmosphere is used in which gases are withdrawn with the water vapors, an exhauster could be used, and

then the gases dehydrated and purified and returned to the furnace.

It is evident that the described mechanism would provide a constant draw throughout the entire heating and combustion ranges. This draw would be independent of the method of firing the furnace. The draw can be easily and definitely controlled to suit particular conditions.

Inasmuch as a positive and complete removal of the vapors is effected over a high range of temperatures, less sealing medium need be used since higher temperatures can be permitted and the vapors still adequately removed. This results in a reduction of water cost for the seal; also, a savings in pumping and cooling charges, if recirculated water is used. When oil or some such other sealing medium is utilized, which must be recirculated and cooled, a reduction in oil cost and pumping and cooling charges is effected.

The unimpaired wall structure adds considerable strength permitting a wall overhang which prevents considerable heat loss by radiation.

Also, the invention is applicable, to eliminate sand or other type seals, with the advantages noted, to types of furnaces, such as electric furnaces, in which a liquid type of sealing is not otherwise so essential.

What I claim is:

1. An industrial furnace having an enclosing wall and dome structure, and a hearth spaced from the wall forming a combustion chamber above the hearth, the combustion chamber communicating with the space between the wall and hearth, waste gas flues communicating with the combustion chamber, means for rotating the hearth, a liquid seal exteriorly of the hearth and below said space, a dip plate depending from the wall into the seal, a series of spaced pipes intersecting the dip plate and tapping the area adjacently above the liquid seal, and a suction device communicating with the outer ends of the pipes.

2. An industrial furnace having an enclosing wall and dome structure, and a hearth spaced from the wall forming a combustion chamber above the hearth, the opposed wall and hearth surfaces being sloped and substantially parallel, the combination chamber communicating with the space between the wall and hearth, waste gas flues communicating with the combustion chamber, means for rotating the hearth, means for raising and lowering the wall and dome structure, a liquid seal exteriorly of the hearth and below said space, a dip plate depending from the wall into the seal, a series of spaced pipes intersecting the dip plate and tapping the area adjacently above the liquid seal, a header communicating with the outer outer ends of the pipes, a blower, an open-ended outlet pipe from the latter, and a valve-controlled pipe communicating at one end with the header and at the other end intersecting the outlet pipe.

3. An industrial furnace having an enclosing wall and dome structure, and a hearth spaced from the wall forming a combustion chamber above the hearth, the combustion chamber communicating with the space between the wall and hearth, a water seal for said space, waste gas flues communicating with the combustion chamber, a valve-controlled conduit extended from exteriorly of and below the wall and tapping the area adjacently above the water seal, and a valve-controlled Venturi-type aspirating device with which the outer end of the conduit communicates.

4. An industrial furnace having an enclosing wall and dome structure, and a hearth spaced from the wall forming a combustion chamber above the hearth, the combustion chamber communicating with the space between the wall and hearth, a water seal for said space, waste gas flues communicating with the combustion chamber, a valve-controlled conduit extended from exteriorly of and below the wall and tapping the area adjacently above the water seal, burners discharging into the combustion chamber, a blower having an outlet furnishing combustion air to the burners, and a valve-controlled open-ended pipe communicating with the outlet between the blower and the burners, said conduit at its outer end communicating with the pipe.

5. An industrial furnace having relatively movable parts and formed with a combustion chamber, waste gas flues tapping the combustion chamber, an opening between the furnace parts having communication with the combustion chamber, a liquid seal for the opening, and a pipe passed into the furnace exteriorly of the relatively movable parts thereof and having an inner end portion tapping the area adjacent the chamber side

of the liquid seal, said pipe exteriorly of the furnace wall communicating with a suction-producing device.

6. An industrial furnace having a wall and dome structure enclosing a combustion chamber, a hearth spaced from the wall and disposed below the combustion chamber, the latter communicating with the space between the wall and hearth, waste gas flues tapping the combustion chamber, means for rotating the hearth, a liquid seal surrounding the hearth, said space communicating with the seal, a dip plate depending from the wall into the seal, burners for firing the furnace, a combustion air pipe communicating with the burners, a blower effective upon said pipe, an open-ended pipe communicating with the first-mentioned pipe between the blower and the burners and having a Venturi section, a series of pipes intersecting the dip plate and tapping the area adjacently above the liquid seal, a header for said series of pipes, and a pipe communicating at one end with the header and tapping the Venturi section with its opposite end.
